SPICE CABINET

Joseph B. Szewczyk, Pittsburgh, Pa., assignor to Creative Products Company of America, Pittsburgh, Pa.

Filed Feb. 21, 1963, Ser. No. 73,672

Term of patent 14 years

(Cl. D44—6)

Fig. 1.

Fig. 2.

Fig. 3.

FIGURE 1 is a three-quarter perspective frontal view of a spice cabinet showing my new design;

I claim:

The ornamental design for a spice cabinet, as shown.
